PIANO STRING-PLATE MOUNTING

Henry Forbes Russell, Quincy, Mass.

Application March 13, 1952, Serial No. 276,377

1 Claim. (Cl. 84—185)

1

This invention relates to a piano string-plate, and particularly to the mounting of the string-plate and the strings, and has as one of its major objects to provide a new construction whereby the length of the string-plate in a spinet-type piano may be substantially increased, thereby providing means to better the quality of the tone, and, whereby a so-called "large upright" piano may be successfully converted to a modern spinet-type piano.

Another object of this invention is to retain the original string-plate and strings in the conversion of the large upright piano to the spinet-type piano.

Another object of this invention is to provide a new construction for the mounting of the string-plate and the strings, whereby the full 88-note keyboard may be retained.

Another object of this invention is to provide a new construction for the string-plate and strings of a spinet-type piano which will substantially reduce the cost of such a piano.

For these objects and other objects that shall become apparent, I shall now show and describe, first in limited form and then in full detail, the construction and combinations of my invention and the manner in which the same is to be made and used.

In the accompanying drawing Fig. 1 is a left-side view, with the side-casing removed, of the string-plate mounting and the strings extending below the vertical frame members comprising the floor-supports.

Fig. 2 is a front view, with the action, desk and side-casings removed, of the string-plate mounting and the strings extending below a pair of side vertical frame members comprising floor-supports.

It is well known that attempts have been made to reduce the height of large upright pianos down to the size of the modern spinet piano, and that such attempts have shown the matter to be an exceedingly stubborn problem.

My desired construction, as herein described and shown, is the result of many months of actual work upon six different pianos, and shows the construction of a "real" conversion of a large upright piano 54 inches high to a spinet-type piano only 38 inches above the floor.

In Fig. 1 is shown one of two side vertical frame members 1 comprising a floor-support, and made of wood, and having a tenon 1A at its upper extremity whereby it is secured to a pin-block 2 made of wood and having a mortise adapted to receive the said tenon. Now further,

2

is shown one of a plurality of full-length vertical frame members 3, made of wood, and secured at their upper extremities in the said pin-block 2, and having their lower extremities extending substantially below the said floor-support 1. The term "full-length" as used herein denotes the original length of any part as it was in any one large upright piano.

Now further in Fig. 1 is shown a plurality of 10 ribs 4, made of wood and secured to the said vertical frame members 1 in the usual manner, preferably by gluing. Again is shown a sounding-board 5 made of wood and secured to the said ribs in the usual manner, preferably by gluing; moreover is shown the said sounding-board extending substantially below the said floor-supports 1.

Further is shown a piano string-plate 6 made 20 preferably of cast iron and secured at its upper extremity to the said pin-block 2 by a plurality of suitable screw-bolts 7, the lower extremity of the said string-plate extending substantially below the said floor-support 1, and being secured at its lower extremity to the lower extremities of the 25 said plurality of full-length vertical frame members 3 by means of suitable screw-bolts 7.

Again is shown a tuning-pin 8 made preferably of steel and secured in the said pin-block 2. A piano string 9 made preferably of steel is secured at its upper extremity in the said tuning-pin 8 and its lower extremity extends below the 30 said floor-support 1, substantially, and to the original full length and the original position of this string in the large upright piano; the lower 35 extremity of the said string 9 being secured to the lower extremity of the said string-plate 6 by means of a hitch-pin 10, the said hitch-pin 10 being made preferably of steel.

Now further, is shown in dotted lines the size, 40 position and height of the desk 11 in its relation to the string-plate mounting. The desk, including the feet, is moved upward until it is substantially flush with the top of the pin-block.

Further, in assembling a spinet-type piano, 45 based upon the new construction of my string-plate mounting, the full-length side casings on both sides are cut-off at the lower extremity of the said floor-support 1. The floor-board, supporting the pedal action, is moved-up to and secured to the said floor-supports 1, on both sides, a small area being cut-out of the floor-board to pass the full-length vertical frame members, the string-plate and the strings.

Further, in assembling a spinet-type piano, 50 based upon the new construction of my string-

plate mounting, the action is positioned in the exact same position, relative to the string-plate, as it had in the original large upright piano; the securing of the action, however, is now made to the said side casings or down to the newly positioned floor-board by means of two upwardly positioned blocks from the said floor-board. The connection between the action and the keys is made by the well-known construction of the "inverted sticker."

Now further, in Fig. 1 is shown in section, two adjacent beams 12, 12 of the floor of a living-room or hall, and the rough floor 13 on the said beams, and the finished floor 14 on the said rough floor. Further is shown a slit in the finished floor and the rough floor, the said slit permitting the full-length vertical frame members 3, the full-length string-plate 6, the full-length sounding-board 5 and the full-length piano strings 9 to pass down thru the said floor. Again is shown the cut side vertical frame member 1 comprising a floor-support resting on top of the said floor and supporting the said vertical frame members 3, the sounding-board, the string-plate and the piano strings.

Now in Fig. 2 is shown a front vertical view of the new construction in my piano string-plate mounting, and is shown this view on the vertical line A—B of Fig. 1; moreover, this view is shown with the piano desk removed. Now further in Fig. 2 is shown an entire section of the middle of the string-plate mounting cut-out, in order to show the two side vertical frame members cut-off from the bottom in the length equal to the height that the string-plate is to be lowered above the floor; moreover, the said cut side vertical frame members are shown comprising floor-supports for the string-plate mounting.

Now further, in Fig. 2 is shown two side vertical frame members 1, made preferably of wood, and cut-off at their lower extremities an amount in inches that it is desired to lower the string-plate, this amount being approximately 22 inches; moreover, is shown the said vertical frame members 1 comprising floor-supports by resting on the floor 14.

Again is shown a pin-block 2, made preferably of wood, and secured to the said vertical frame members 1 by means of a mortise and tenon 1A. Again is shown a plurality of vertical frame members, made preferably of wood, 3 and of full or desired length, and secured at their upper extremities in the said pin-block 2 and by means of mortises and tenons 3A, and having their lower extremities extending substantially below the said floor-supports 1.

Further is shown a plurality of sounding-board ribs 4 made preferably of wood, and secured to the sounding board 5 in the usual manner, and preferably by gluing. Again is shown the sounding board 5 made preferably of wood, and secured preferably to the two said vertical frame members comprising floor-supports 1. Moreover, is shown the said sounding-board 5 extending substantially below the said floor-supports 1, and secured at its lower extremity to the lower extremities of the said full-length vertical frame members 3, by means of suitable screw-bolts, made preferably of steel 15.

Now further, is shown the piano string-plate 6 made preferably of cast iron and secured at its upper extremity to the said pin-block 2 by a plurality of suitable screw-bolts 7; the said string-plate having its lower extremity extending substantially below the said floor-supports 1, and

being secured at its lower extremity to the lower extremities of the said vertical frame members 3 by means of suitable screw-bolts 7.

Again is shown a tuning-pin 8 made preferably of steel and secured in the said pin-block 2. A piano string 9 made preferably of steel is secured at its upper extremity in the said tuning-pin 8 and its lower extremity extends substantially below the said floor-supports 1 and to the original full-length or desired length, and at the original position of this string in the large upright piano; the lower extremity of the said string 9 being secured to the lower extremity of the said string-plate 6 by means of a hitch-pin 10, the said hitch-pin 10 being made preferably of steel. Obviously, the piano string 9 represents one of a plurality of such piano strings.

Now further is shown a beam of the floor of a living-room or hall 12, and is shown the said vertical frame members, the sounding board, the string-plate and the strings positioned down between and parallel to the said beams 12, and, all substantially below the said vertical frame members 1, comprising the floor-supports. Again is shown the rough floor 13 on the said beam 12, and the finished floor 14 on the said rough floor 13.

According to my invention, my new string-plate mounting provides an extremely successful construction for converting the large or high upright piano to the new modern low spinet-type piano. Thus, I have retained the original length, size and design of the string-plate, and the original length and position of the strings mounted thereon; thereby retaining also the original scale of the string-plate, and the original beautiful tone and the original craftsmanship.

According to my invention, my new string-plate mounting provides means for a full 88-note keyboard which is highly desirable.

According to my invention, my new string-plate mounting provides means to make a successful conversion without the increment of any major parts.

According to my invention, my new string-plate mounting provides the basis for a successful assembly of the three remaining major parts, namely the desk, the action and the keys; the said assembly being relatively easy to execute by one skilled in the art.

Certain disadvantages are obvious; but these have been carefully considered and weighed, and have been found to be definitely out-weighed by a number of highly desirable qualities.

Thus, as undesirable, it is obvious that an area of flooring of approximately 8 inches by 40 inches must be taken up in order to allow the string-plate, sounding-board and vertical frame members to pass down between the beams. Again, the piano must stay in one position, and can not be moved or turned in the ordinary sense. Moreover, this construction is adaptable, generally, to the first floor only, and not to a second or third floor. And finally, my construction, in its installation, is governed by the direction of the beams under the room; thus this construction must go down parallel between the beams and can not go across the beams.

The highly desirable qualities of a spinet-type piano having my new string-plate mounting are exceedingly attractive and are immediately observed in the increased quality of the tone, the full appearance of the 88-note keyboard, the ability of the piano to maintain an A-440 pitch, and to stay in tune for long periods of time, the

normal appearance of the piano and the low 38 inch height of the piano above the floor, the original sturdy construction and the master craftsmanship of all the major parts, the ease by which the conversion may be made by a skilled piano technician, and lastly, and very important, the relatively low cost of the finished product, assembled, transported and installed.

In the technique of the actual construction of my new string-plate mounting, referring first to Fig. 1, the distance C—B is approximately 6 inches; and, referring to Fig. 2, the sounding-board is also cut-in from both sides a distance D—E and F—G of approximately 10 inches each; and, the distance E—F is governed by the width of the cast-iron string-plate at its lowest point, and is approximately 40 inches. Some string-plates, at this position, have cast-iron struts at each side, which are preferably cut-off in order to make the distance E—F as small as possible. Again, I have found that I can perform the entire conversion from a large upright piano to a low modern spinet-type piano without letting-off any of the string tension. Thus, I have maintained the A-440 pitch and the entire number of strings in tune while the two outer vertical frame members were cut; and have found that the remaining three or four full length vertical frame members have amply provided the reinforcement required by the string-plate. This accomplishment has been of tremendous value and importance in the successful construction of my new string-plate mounting.

This piano is installed by cutting a hole in a floor 13 such that the lower portion of the vertical frame members 3 slide through, but the floor supports 1 remain above the floor.

Again, the cutting of the sounding-board proved equally successful, in that no cracks appeared as a result of the cutting; moreover, no displacement from the original setting of the sounding-board could be observed.

According to the construction of my invention, I have found that I, alone, can fully and successfully convert a large upright piano to a low modern spinet-type piano in three working days of eight hours each.

I am concerned to say that my new construction comes at a time badly needing such an improvement; for, the low esteem to which these beautifully toned instruments has fallen can be seen in the fact that they are being given away free to anyone willing to pay the moving charges.

I am aware that prior to my invention, certain changes have been made in large upright pianos to make such pianos look lower in height. I am not concerned with this. I am aware that prior to my invention, spinet-type pianos have employed in the "inverted sticker" construction, I am therefore not concerned with this. I am aware that prior to my invention, many improvements have been made in piano string-plates. I am therefore not concerned with these.

I claim:

The method of installing an upright piano of the type in which the string-plate extends beyond the casing and in which the casing has a larger cross-sectional dimension than the string-plate which comprises cutting a hole in a floor, said hole having a dimension which is smaller than said dimension of said casing and larger than the corresponding dimension of the string-plate and inserting the lower end of the string-plate into said hole.

HENRY FORBES RUSSELL.
